HUMIDIFIER FOR INTERNAL-COMBUSTION ENGINES

James F. Talbott, Baltimore, Md.

Application August 21, 1942, Serial No. 455,679

4 Claims. (Cl. 261—99)

1

My invention relates to internal combustion engines, and has among its objects and advantages the provision of an improved fuel system wherein water vapors are blended with the fuel to increase engine operating efficiency, eliminate carbon and to effect economy in fuel consumption.

In the accompanying drawings:

Figure 1 is a diagrammatic top plan view of the system as applied to an internal combustion engine of the type employed in automotive vehicles.

Figure 2 is a side view.

Figure 3 is an enlarged sectional view along the line 3—3 of Figure 1.

Figure 4 is a sectional view along the line 4—4 of Figure 3.

Figure 5 is a sectional view along the line 5—5 of Figure 3.

Figure 6 is a sectional view along the line 6—6 of Figure 3.

Figure 7 is a cross sectional view of the exhaust pipe of the vehicle illustrating a gas trap mounted thereon.

Figure 8 is a sectional view along the line 8—8 of Figure 7.

Figure 9 is a sectional view along the line 9—9 of Figure 8.

Figure 10 is a sectional view of a water feeding jet.

Figure 11 is a partial sectional view of the greater part of the system illustrating the parts thereof separated one from the other, and

Figure 12 is a sectional view of a modified system.

In the embodiment of the invention selected for illustration, I make use of a water tank 10 which is preferably mounted on the usual air inlet pipe 12 of a conventional carburetor 14, see Figures 1 and 2. This carburetor has communication with the intake manifold 16 of the engine 18 in the conventional manner.

The tank 10 is attached to a vaporizer 20, see Figure 3. This vaporizer includes a pan 22 closed at its upper end by a sheet 24 of copper wire mesh and a resilient gasket 26 interposed between the mesh and the bottom 28 of the tank 10. The purpose of the gasket 26 is to seal the tank 22 and insulate it from the water in the upper tank, so that the heat of these gases flowing in the spiral passage is not dissipated. Figure 6 illustrates the contour of the pan 22 when viewed from the top. This pan is provided with a central and open ended tube 30 coaxially arranged inside a tube 32, see Figure 3, fixedly secured to

2

the bottom 28 and extending through an opening in the top wall of the tank 10. The tube 30 is of smaller diameter than the tube 32 to provide an annular space 34 for the accommodation of four vertical bolts 36 for clamping the tank 10 and the vaporizer 20 into a unitary structure.

The bolts 36 are welded to the tube 32 and extend through openings 38, see Figure 12, in a plate 40 lying on the upper end of the tube 32. Wing nuts 42 are threaded on the bolts 36 for fixedly relating the tank and the vaporizer. Openings 44 are provided in the tube 32 above the top wall of the tank 10 and underneath the plate 40. A screen 46 is arranged across the openings 44.

In Figure 6, a vertical and spirally contoured wall 48 is arranged inside the pan 22. This wall is welded edgewise to the bottom of the pan, and the convolutions 50 of the wall are spaced sufficiently far apart to provide accommodation for a spirally contoured copper tube 52 having upwardly directed openings 54 for the delivery of water from the tank 10 to the vaporizer 20. Transverse arms 56 connect with the convolutions 50 to constitute a support for the tube 52.

The ends of the tube 52 are closed by copper mesh walls 58, one wall 58 being attached to the tube 30 and the innermost convolution 50 and the second wall attached to the two outermost convolutions. A tube 60, see Figure 10, has communication with the tube 52 and serves as a socket for the reception of a depending tube 62 attached to the tank bottom 28 and communicating with the tank. Inside the tube 62 is threadedly mounted a jet plug 64 having a small bore 66 for the passage of water from the tank 10 into the vaporizer 20. A screw driver slot 68 is provided in the lower end of the plug 64 to facilitate placement and removal thereof. Jet plugs of different sizes may be substituted to satisfy the requirements of different engines and operating conditions.

Attached to the tank bottom 28 coaxially of the tube 62 is a larger diameter tube 70 having openings 72 near its bottom end for the passage of water. The tube 70 extends through an opening 74 in the top of the tank 10, see Figure 3.

Inside the tube 70 is movably mounted a valve 76 for controlling the flow of water from the tank 10 and into the tube 52. This valve includes a rubber disk 78 secured to a metallic disk 80, both of which are slidably freely inside the tube 70, with the rubber disk 78 engageable with the bottom wall 28 in the closed position of the valve. A stem 82 is attached to the disk 80 and is slid-

able freely in a small bore 84 in a cork body 86 inserted in the upper end of the tube 70. A small tension compression spring 88 is interposed between the disk 80 and the cork body 86.

A lever 90 is pivotally mounted intermediate its ends on a post 92 attached to the top of the tank 10. One end of the lever 90 is pivotally connected with the upper end of the stem 82 and the other end of the lever is pivotally connected with a stem 94 attached to a suction responsive piston 96.

The piston 96 is slidably mounted in a bore 98 of a cup 100 extending through an opening 102 in the top of the tank 10 and fixedly secured thereto. The piston 96 includes a leather washer 104 mounted between metallic disks 106 fixed to the stem 94. The washer 104 is of slightly larger diameter than the bore 98 so as to form a sealing flange about the perimeter of the washer.

Communicating with the bore 98 and underneath the piston 96 is a suction tube 108, this tube extending through the bottom 28 but welded thereto to provide a watertight joint. The lower end of the tube 108 is connected with a pipe 110, see Figures 1 and 2, having communication with the intake manifold 16. Operation of the engine creates a low pressure condition effective in the chamber 98 for pulling the piston 96 downwardly and lifting the valve 76 off its seat.

The valve 76 is lifted a short distance only. The tension of the spring 88 is merely sufficient to overcome resistance of the movable parts of the valve structure and to insure closing of the valve 76 when the engine is stopped.

The cup 22 is filled with non-rusting steel wool and sponge 112, the tube 52 being buried in this filler.

Figure 6 illustrates the cup 22 as being provided with a corner chamber 114 having communication with the space between the outermost convolution 50 and the side wall of the cup. This chamber is provided with a depending tube 116 for connection with a hose 118 leading to a gas trap 120 mounted on the exhaust pipe 122 slightly rearwardly of the usual muffler with which such pipes are provided, see Figures 7, 8 and 9. The hose 118 connects with a tube 124 extending into a housing 126 having communication with the exhaust pipe 122 through the medium of a plurality of ports 128. The housing 126 is welded to the exhaust pipe and is additionally made secure by clamps 130 extending about the exhaust pipe.

Inside the housing 126 is arranged a triangularly shaped housing 132 having a suitable wire mesh wall 134 arranged horizontally above the exhaust pipe 122. The tube 124 extends through the housing 132 and is slotted at 136 for the entrance of gas to be passed to the vaporizer 20. A wire screen 138 extends about the tube 124 inside the housing 132, the latter having end engagement with the end walls of the housing 126 and fixedly secured thereto. The two walls of the housing 132 other than the mesh wall 134 diverge downwardly and are imperforate. Thus the slotted tube 124 is protected to prevent the entrance of carbon and other solids which might accumulate in and pass through the exhaust pipe. Gases entering the housing 132 must pass through the mesh 134, the latter serving as a screen to prevent the entrance of objectionable solids.

A portion of the exhaust gases are delivered to the vaporizer 20 for converting moisture therein into the form of vapor passing into the tube 30 through an opening 140 in a neck 142 extend-

ing inwardly of the tube 30. Fixed to the neck 142 is a body 144 having a bore 146 communicating with the opening 140 and passing through the lower end of the body. The neck 142 is welded to the tube 30.

In operation, exhaust gases back through the hose 118 and enter the vaporizer 20. These gases are sucked through the filtering body 112 to supply air for mixture with the fuel from the carburetor 14. The exhaust gases entering the vaporizer 20 are humidified, and the carbon monoxide is absorbed in its passage through the spiral passageway to the engine.

The tube 52 is wound to provide at least four convolutions inside the cup 22. This coiled tube supplies the water to the filter body 112 so that the latter is maintained in a moist condition and dustless. The jet plug 64 is selected to supply the necessary flow of water, which may flow in a dripping condition. The flow should be such as to prevent the accumulation of free flowing water in the cup 22.

It will thus be seen that the system operates to effectively maintain a moisture condition which coacts with the carburetor in such manner as to provide an efficient fuel mixture for the engine. This system renders the engine more efficient in its operation, eliminates objectionable carbon formation and effects economy in fuel consumption.

In case of engine backfire, Figure 3 illustrates the body 144 as being provided with a bore 148 within which is slidably mounted a rod 150 having a plate valve 152 attached thereto and normally lying at rest on the upper end of the tube 30. This plate valve is yieldingly biased to its normal position by means of a compression spring 153 interposed between the bottom face of the bore 148 and a plate 154 attached to the rod 150. Thus backfiring pressure causes the plate valve 152 to lift off the tube 30 and pass the gases into the tube 32 for delivery to the atmosphere through the openings 72. The plate 154 constitutes a stop engageable with the body 144 to limit the upward movement of the plate valve 152, and to close the bore 148 to prevent dirt, gas and the like from being blown into the filter.

Splash eliminating partitions 156 are provided in the tank 10.

The bottom of the cup 22 is provided with a spirally shaped depression 158 located so that its convolutions underlie the convolutions of the tube 52. This depression communicates with the tube 116 to which the exhaust hose is connected.

Figure 12 illustrates a modification in that the vaporizer 160 and the water tank 162 are separate. The vaporizer 160 may be mounted in the same manner as the vaporizer 20 but the detached association of the vaporizer and the water tank permits the latter to be mounted in any desired place on the vehicle.

The cup 164 of the vaporizer 160 is provided with a cover plate 166 having a conically shaped hood 168 welded thereto and to the tube 170 corresponding to the tube 32. A flexible tube 172 has one end connected with a tube 174 corresponding to the tube 60 of Figure 10, and the other end of the tube is connected with a valve 176 having communication with the tank 162. Both water and air valves 178 and 180 are similar to the valves 76 and 96, respectively. The lever mechanism 182 is enclosed in a cap 184 clamped against a resilient seal 186 on the top of the tank 162. Posts 188 are welded to the top

of the tank and threadedly receive screws 190 for attaching the cap to the posts.

In other respects, the structure of Figure 12 operates identically with that of Figures 1 through 11.

Both cups 22 and 162 are provided with reinforcing plates 192 at their bottoms, which plates are welded to the tube 30 and the tube 194, respectively.

Without further elaboration, the foregoing will so fully explain my invention, that others may, by applying current knowledge, readily adapt the same for use under various conditions of service.

I claim:

1. A vaporizer comprising a casing having an inlet for air and an outlet for humidified gas and a spiral passage extending from the inlet to the outlet a sheet of copper wire mesh over the top of said casing, a resilient gasket on said mesh to insulate and close said casing, an absorbent packing in said passage, and a spiral water supply tube located in said passage embedded within said packing and provided with spray openings, the tube being provided with a water inlet opening.

25

2. A vaporizer comprising a casing having an inlet for air and an outlet for humidified gas and a spiral passage extending from the inlet to the outlet a sheet of copper wire mesh over the top of said casing, a resilient gasket on said mesh to insulate and close said casing, an absorbent packing in said passage, a spiral water supply tube located in said passage within said packing provided with spray openings, the tube being provided with a water inlet opening, and a spiral depression in the bottom of said casing underlying and conforming with the convolutions of said spiral water supply tube, said depression constituting a passage from said inlet to said outlet.

3. The invention described in claim 2 wherein the outlet of said casing is provided with a pressure controlled valve.

4. The invention described in claim 2 wherein said casing is provided with supports for said spiral water supply tube.

JAMES F. TALBOTT.
